UNITED STATES PATENT OFFICE.

SIDNEY LEETHAM AND RICHARD EDMUND LEETHAM, OF YORK, ENGLAND.

AUTOMATIC FEED WEIGHING AND PACKING APPARATUS.

No. 858,728.

Specification of Letters Patent.

Patented July 2, 1907.

Application filed April 30, 1906. Serial No. 314,579.

To all whom it may concern:

Be it known that we, SIDNEY LEETHAM, residing at Elmbank, York, and RICHARD EDMUND LEETHAM, residing at Bootham, York, both in the county of York, 5 England, subjects of the King of Great Britain, have invented new and useful Improvements in Automatic Feed Weighing and Packing Apparatus, of which the following is a specification.

Our invention relates to apparatus for feeding material into sacks or other receptacles and weighing the same and to that class of such apparatus wherein the material is first fed into the sack or other receptacle until the larger part is filled, the packing being then automatically stopped and the remaining portion, required for insuring an accurate weighing, being quietly fed into the receptacle until the feed is entirely stopped through the medium of the movement of the beam of the weighing machine.

According to our invention we make use of a beam 20 balance and feed and packing mechanism for the material in conjunction with a holder for the sack, barrel or other receptacle into which the material is to be packed and weighed. The packing is effected by means of a device which compresses it into the receptacle and the arrangement may be used either with or without independent valves for controlling the supply.

In carrying out our invention we make use of a single or double pitch screw which is mounted upon a spindle 30 adapted to be revolved by suitable means. Where a sack or bag is the receptacle for the material it is suspended from a mouth-piece on the balance beam, and in one construction the said bag may be initially gathered up around the said mouth-piece with its lower end 35 resting upon a table or support. As the material operated upon by the revolving screw packer gradually fills the sack, the support or table is lowered until it reaches a certain position when it is automatically caused to drop suddenly, leaving the sack hanging freely on the mouth-piece to receive the final slight addition of material to obtain an accurate weight; when this is obtained the feed is cut off by the movement of the beam. Or, in lieu of providing a sack support or table which falls as above described, we may make use 40 of a machine wherein the packer screw itself moves axially, and in this case the sack is freely suspended without folding or gathering on to the mouth-piece, and the screw which has vertical movement, is, at the commencement of the filling operation, lowered into the 45 sack and, as it fills the same, gradually rises. When the sack is nearly filled the screw is raised out of the same by suitable means, such as a stop in connection with its spindle which actuates releasing mechanism of any convenient kind, and it then slowly feeds in the 50 material until the correct weight is obtained when the feed is cut off by the movement of the beam. The

screw may in any case be used in combination with a separate valve in the feed hopper which is controlled by the beam as above described. Or, the screw may itself form the valve in which case it revolves in its 60 uppermost position in a casing, the feed being cut off by the movement of the beam putting the driving mechanism out of gear. Furthermore, the screw may be arranged to revolve permanently within a casing and may then itself form the feed valve or be used in conjunction with a separate valve operating as above described.

Where the material is to be packed into barrels, the screw may revolve in a fixed position in which case the barrel is mounted upon a table which rises and falls as 70 above described with reference to the sack filler. When the barrel has been nearly filled, the table, which has gradually descended, brings the barrel to rest upon a tray or the like suspended from the weight-beam and itself moves to its lowermost position out of 75 contact with the barrel. In this position the material is fed into the barrel for the final weigh, and, when the accurate weight is obtained, the beam descends and cuts off the feed as mentioned above. Or, the screw packer may be of the rising and falling kind which itself 80 may form the feed valve with or without the rising and falling casing or which is used in combination with a separate feed valve operated as above described. In this case the barrel is advantageously placed upon a tray or the like suspended from the weigh-beam and may be 85 in combination with a table moving vertically. The tray may be supported upon a balanced lever by releasing which the filled and weighed barrel may be lowered to the ground for facilitating its removal.

To enable the invention to be fully understood, we 90 will describe it by reference to the accompanying drawings, in which:—

Figure 1 is a side elevation of a portion of a weighing machine constructed according to the invention and designed for filling sacks. Fig. 2 is an end view there- 95 of. Fig. 2^a is a view of certain parts shown in Fig. 2, but in another position. Fig. 3 is a view similar to Fig. 1 illustrating a slight modification. Figs. 4 and 5 are views respectively similar to Figs. 1 and 2 of a machine adapted for filling barrels. Figs. 6 and 7 are views 100 similar to Figs. 4 and 5 respectively of a modified arrangement of machine for filling barrels, and Fig. 8 is a view of a further modification of the machine adapted for filling sacks.

Referring first to the construction of machine illus- 105 trated in Figs. 1 and 2, *a* is the frame of the weighing machine and *b* is the weigh-beam, *c* being the mouth-piece which is suspended from the weigh-beam in the ordinary manner, and *d* the sack attached to the lower end of the mouth-piece *c*. *e* is the chute down which 110 falls the material which is to be filled into the sack *d*, this chute opening at its lower extremity into the an-

nular casing *f* which opens into the mouth-piece *c*. *g* is the screw which, in its uppermost position, is located within the aforesaid casing *f*, the said screw *g* being mounted upon the spindle *g*¹ which extends upwards through a bearing *g*² upon the upper end of the casing *f*. The spindle *g*¹ can move axially through the bearing *g*² and is suspended at its upper end from the cord or rope *g*³ which passes around the pulley *g*⁴ and carries the counter-weight *g*⁵, the other end of the cord passing around the guide pulley *g*⁶ and terminating in the handle *g*⁷. The spindle *g*¹ carries the bevel wheel *h* gearing with a similar wheel *h*¹ upon a spindle *h*² carried in the bracket *h*³ and having loosely mounted upon it the driving pulley *h*⁴. The spindle has also keyed upon it the clutch *h*⁵ by means of which the pulley *h*⁴ can be locked to the spindle *h*² so as to rotate the same and thereby the spindle *g*¹ through the medium of the bevel wheels *h*, *h*¹. The clutch *h*⁵ is controlled by one arm of a bell-crank lever *h*⁶ carried on the pivot shaft *h*⁷ which has also keyed upon it the handle or lever *h*⁸ by means of which the clutch can be caused to engage with the pulley as shown in Fig. 2. The other arm of the bell-crank lever *h*⁶ has pivoted to it the link *h*⁹ the lower end of which is formed with a hook *h*¹⁰ which 25 engages with a hook *h*¹¹ attached to the beam *b* of the weighing machine. The pulley *g*⁴, during the operation of the machine, is held from rotation by means of the brake block *i* which is mounted upon one end of a pivoted weighted lever *i*¹; this lever has hinged to it one end of a link *i*², the other end of which is pivoted to a bell-crank lever *i*³ having suspended from it the hooked link *i*⁴; the brake block *i* is automatically operated as hereinafter described by the tappet *j* upon the upper end of the spindle *g*¹ for locking and releasing the pulley *g*⁴ as required.

The operation of this machine is as follows, that is to say, assuming that the sack *d* is suspended from the mouth-piece the attendant pulls the handle *g*⁷ downwards so as to allow the screw *g*¹ to fall to the lowest position as shown in broken lines in Figs. 1 and 2 the tappet *j* coming into contact with the hook on the link *i*⁴ as shown in Fig. 2^a and causing the bell crank lever *i*³ to rock on its pivot and allow the brake block *i* to be pressed against the pulley *g*⁴ by the weight on the lever *i*¹. The handle *h*⁸ is then operated so as to put the clutch *h*⁵ into engagement with the pulley *h*⁴ thereby starting the rotation of the screw *g*. As the material is filled into the sack and compressed the pressure exerted gradually raises the screw *g* which continues to rise until it reaches the intermediate position also shown in broken lines in Fig. 2. When the screw has reached this position the tappet *j* upon the upper end of the spindle *g*¹ strikes the bell-crank lever *i*³ as indicated in dotted lines in Fig. 2^a and so lifts the lever *i*¹ to withdraw the brake block *i* from the periphery of the pulley *g*⁴ which, being thus released, permits the screw *g* to be raised under the action of the weight *g*⁵ until it reaches its uppermost position, that is to say, the position in which it is inclosed in the casing *f*. The bell crank lever *i*³ is rocked upon its pivot by the said upward movement of the tappet *j* to such an extent that the weight on the lever *i*¹ holds the lever *i*³ against a stop *i*⁵ out of the path of the tappet so that the latter when again lowered is not obstructed. The screw continues rotating so as to slowly feed the final quantity

of material into the sack and when the sack contains a predetermined quantity, the beam *b* is over-balanced and moves downwards; the downward movement of the beam causes the hook *h*¹¹ to draw the link *h*⁹ downwards and thus disengages the clutch *h*⁵ from the pulley *h*⁴ so as to stop the rotation of the screw *g* and thus the feeding of the material into the sack.

Fig. 3 shows an arrangement which is identical with that above described with the exception that the screw revolves in an extended casing *f*¹ which is connected to and rises and falls with it, the connection being similar to that hereinafter described with reference to Figs. 4 and 5.

In Figs. 4 and 5 we have illustrated a machine for filling barrels. In this construction the barrel *k* is placed upon a tray *l* suspended from the beam *b* of the machine and the screw *g* works in a casing *f*¹ which rises and falls with it as is the case with the construction illustrated in Fig. 3, rods *f*² and a crosshead *f*³ connecting the casing to the screw. The method of operating the screw and of cutting off the feed is identical with that shown in Figs. 1 and 2. To facilitate the removal of the barrel after it has been packed, the table, during the filling operation, is supported upon the arm *m* which is pivoted at *m*¹ and is held in the horizontal position by means of the weighted arm *m*². When the barrel has been filled the weighted arm *m*² is turned down into the position shown in dotted lines in Fig. 4, thus lowering the arm *m* and permitting the table *l* to drop so as to enable the barrel *k* to be more conveniently removed.

Figs. 6 and 7 illustrate a construction of apparatus for filling barrels wherein the barrel itself rises and falls, the screw packer being fixed. To this end the barrel *k* is placed upon the platform *n* which is connected to a sliding carriage *o* running upon the frame *a* of the machine. The said carriage *o* is connected to one end of a rope *o*¹ which runs around a pulley *o*² provided with a band brake *o*³ held applied by the weighted lever *o*⁴ and thence around the fixed guide pulley *p*, its other end being connected to the spring *p*¹ which is attached to a rigid bolt *p*³ on the machine frame. The tension of the spring *p*¹ automatically raises the table to the uppermost position shown in the drawings while the table gradually descends under the pressure exerted by the screw *g* as it fills the barrel. When the barrel has been nearly filled its lower end comes to rest upon the tray *q* suspended from the beam *b* of the balance in the manner above described in order that the final weigh may take place. It is therefore necessary for the table to move farther down so as to leave the barrel free upon the tray *q* and to this end the said table is provided with an extension *n*¹ having a screw threaded hole *n*² which, when the barrel comes to rest upon the tray, engages with the upper end of the screw *r* rotatably held in a bearing *r*¹ in the machine frame and having keyed upon its lower end a bevel pinion *r*² gearing with a bevel pinion *r*³ upon a transverse spindle *r*⁴ adapted to be driven from any suitable source of power. The packing screw is driven by bevel gearing *h*, *h*¹ and the pulley *h*⁴ as in the arrangement shown in Figs. 1 and 2 and the clutch for putting the pulley *h*⁴ into and out of operation is controlled by the hook mechanism *h*⁹, *h*¹⁰, *h*¹¹ which is also similar to the arrangement shown in Figs. 1 and 2. This machine operates as fol-
